UNITED STATES PATENT OFFICE.

CHARLES S. EPPLER AND MERVIN E. STONESIFER, OF YORK, PENNSYLVANIA; SAID STONESIFER ASSIGNOR TO SAID EPPLER.

STEAM-COOKER.

No. 850,824.

Specification of Letters Patent.

Patented April 16, 1907.

Application filed March 21, 1906. Serial No. 307,204.

To all whom it may concern.

Be it known that we, CHARLES S. EPPLER and MERVIN E. STONESIFER, citizens of the United States, and residents of York, in the county of York and State of Pennsylvania, have made certain new and useful Improvements in Steam-Cookers, of which the following is a specification.

This invention is an improvement in steam-cookers intended especially for domestic use; and the invention consists in certain novel constructions and combinations of parts, as will be hereinafter described and claimed.

15 In the drawings, Figure 1 is a vertical longitudinal section from front to rear of a cooker embodying our improvements. Fig. 2 is a transverse vertical longitudinal section of the cooker. Fig. 3 is a bottom plan view 20 thereof, partly broken away. Fig. 4 is a perspective view, partly in section, of the boiler; and Fig. 5 shows a somewhat different form 25 of boiler or generator from that shown in the other figures of the drawings.

As shown, the cooker comprises a casing A, divided by a horizontal partition B into an upper steaming-compartment C and a lower baking-compartment D, provided, respectively, with doors C' and D', by which access 30 may be readily had to the different compartments. The bottom D² of the compartment D is elevated or raised above the bottom of the casing, affording boiler-space D³ beneath it for the heating branch E' of the boiler E and for the bottom plate F of the casing, which forms, with the bottom D², the boiler chamber or space D³ at the bottom of the casing in which the heat accumulates 35 surrounding the said heating branch E', as will be understood from Fig. 2 of the drawings.

The boiler is of a special cross-sectional shape, as will be described, and it is spaced at e and e' from respectively the plates F and D², so the heat may circulate entirely around the heating branch E' of the boiler, as best shown in Figs. 1 and 2 of the drawings.

The bottom plate F of the casing is provided with openings f, through which the 45 heat may pass into the boiler-chamber D³, and has a plate f' separating the openings f and extending beneath the heating branch E' of the boiler in such manner as to protect the same from the direct action of the heat

from the stove or other heating medium, 55 upon which the cooker is placed in practice, and the heat passing up through the openings f may circulate freely around the heating branch E' of the boiler to quickly raise the water therein to a steaming-point.

60 Flues G and G' extend upwardly from the boiler-chamber into the baking-compartment and discharge heat thereto. By preference the flue G is elongated from front to rear and distributes the heat evenly at one 65 side of the baking-compartment, while the flue G' is in the form of a pipe having a returned upper end G² and arranged at the opposite side of the baking-compartment from the flue G, as will be understood from Fig. 2 70 of the drawings.

The boiler E has the horizontal or heating branch E' and the upright branch E², communicating at its lower end with the rear end of the branch E' and extending thence up 75 through the bottom D² of the baking-compartment and opening at its upper end into the bottom of the steaming-compartment at the rear end thereof, as will be understood 80 from Figs. 1 and 2. By preference the upper end of the upright branch E² is flanged at e² along the upper side of the bottom B of the steaming-compartment C and may be soldered or otherwise secured thereto, as will be understood from Fig. 2 of the drawings, so 85 that the boiler at its upper rear end is secured to and supported from the bottom B. At its opposite end, or the front end of the heating branch E', the boiler is supported from the casing through the medium of the faucet 90 H, which has its threaded nipple H' extending through the casing and screwed at H² into connection with the front end of the heating branch E' of the boiler, whereby to secure the said boiler firmly at such point in connection 95 with the casing. By this construction the boiler is supported above the bottom of the casing, and the weight of the boiler is supported from the bottom B of the steaming-compartment and the lower portion of the 100 front of the casing, as will be understood from Fig. 1 of the drawings.

In constructing the boiler E it is preferred to form its heating and upright wings or sections from sheets of metal bent to the desired 105 cross-sectional form and secured at their meeting edges by rivets, the rivets of the lower or heating section E' being at the top

thereof and such section having its sides flaring outwardly toward their upper edges, as shown in Figs. 2, 3, and 4 of the drawings.

For filling the boiler we employ a tube I, 5 extending down through the top of the cooker and projecting at its lower end into the open upper end of the boiler and preferably extending down, as shown in Figs. 1 and 2, to a point below the upper side of the heating branch E' of the boiler.

A removable funnel J, fitting in the upper end of the tube I, facilitates the filling operation, and its funnel may be utilized to secure an alarm-whistle J'. When it is desired to 15 renew the water in the boiler, the funnel J may be removed, the whistle J' withdrawn, and the funnel again inserted to direct the water into the tube I.

In Fig. 5 we illustrate a somewhat different 20 form of boiler in which the heating branch designed to be used in lieu of the branch E' is composed of front and rear sections K and K', and pipes K² connect the same, and the upright branch K³ connects with the rear section K' and extends upwardly, as indicated in Fig. 5, to discharge to the steaming-compartment. This construction may be substituted for the construction shown in Fig. 1 25 without departing from some of the broad 30 principles of the invention, and it will be understood that when so substituted the faucet may be utilized to connect the front end of the heating branch with the casing, and the upright branch may be supported from the 35 bottom of the steaming-compartment, as described in connection with the upright branch E² of the form of boiler shown in Fig. 4.

Having thus described our invention, what 40 we claim as new, and desire to secure by Letters Patent, is—

1. The improvement in steam-cookers herein described, comprising a casing having a horizontal partition dividing it into an upper steaming-compartment and a lower baking-compartment, said partition forming the 45 bottom of the steaming-compartment, a bottom for the baking-compartment located

above the bottom of the casing, the casing-bottom plate spaced below the bottom of the baking-compartment and forming a boiler-chamber below the same, said casing-bottom having openings admitting heat to the boiler-chamber and an intermediate plate between the said openings and forming a guard for the boiler, means for conducting the heat 55 from the boiler-chamber into the baking-compartment, a boiler having a horizontal branch extending within the boiler-chamber and above the intermediate plate between the openings in the casing-bottom and an upright branch or section extending from the rear end of the heating branch upwardly to and discharging into the steaming-chamber and supported at said upper end from the bottom of the steaming-compartment and a 60 faucet having its threaded nipple extending through the casing and screwed into connection with the front end of the heating branch of the boiler, all substantially as and for the purposes set forth. 70

2. The combination in a steam-cooker, of a casing having a steaming-compartment and a baking-compartment and provided below the baking-compartment with a boiler-chamber and with a bottom plate for said boiler-chamber and a boiler having a heating branch extending within the boiler-chamber and an upright branch extending to and discharging into the steam-chamber, substantially as set forth. 75

3. The combination in a steam-cooker with a casing provided at its lower end with a boiler-chamber and below the same with a bottom plate having openings and an intermediate plate between the same and a boiler having a heating branch within the boiler-chamber and extending above the said intermediate plate and spaced apart therefrom, substantially as set forth. 80

CHARLES S. EPPLLEY.

MERVIN E. STONESIFER.
